UNITED STATES PATENT OFFICE.

JAMES W. HOUSER, OF HAMMOND, INDIANA, ASSIGNOR TO AMERICAN STEEL FOUNDRIES, OF NEW YORK, N. Y., A CORPORATION OF NEW JERSEY.

TWO-PART REVERSIBLE BRAKE-BEAM FULCRUM.

No. 876,057.

Specification of Letters Patent.

Patented Jan. 7, 1908.

Application filed March 29, 1907. Serial No. 365,274.

To all whom it may concern:

Be it known that I, JAMES W. HOUSER, a citizen of the United States, residing at Hammond, in the county of Lake and State 5 of Indiana, have invented certain new and useful Improvements in Two-Part Reversible Brake-Beam Fulcrums, of which the following is a specification.

My invention relates to brake-beam fulcrums, especially to those of the reversible type, and its object is the production of a two-piece fulcrum which shall be extremely simple in construction, and of which the oscillatory barrel to which the operating 10 lever is pivoted is held in place and maintained in position by the brake-beam itself. The structure is such that this barrel may be readily removed as soon as the yoke or beam-engaging portion of the fulcrum is removed 15 or unclamped from the beam. This barrel is inserted in the companion part of the device through a comparatively large aperture in that part of the fulcrum adapted to lie against the flanges of the brake beam, whereby when the device is fastened to the beam, these flanges hold the barrel in place 20 and prevent its withdrawal.

On the accompanying drawing, I have illustrated a preferred and desirable embodiment of my invention, and, in the various 25 views, like reference characters refer to the same parts throughout.

Figure 1 is a perspective view of my improved two-part reversible fulcrum, and 30 shows the same attached to an I-brake beam; Fig. 2 is an edge view of my improved fulcrum; Fig. 3 is an end view of the same, showing a portion of the operating lever; and Fig. 4 is a top plan view of the device.

The fulcrum includes two parts, one of 40 which is fastened to the brake-beam, while the other part is revoluble in the first part and is adapted to have the operating lever pivoted thereto. The part intended to be secured to the beam has a base 10, projecting from which is a pair of oppositely-disposed flange-engaging hooks 11 and 12, these hooks or gripping lugs being spaced apart sufficiently to receive the brake beam 45 between them. After the beam has once been inserted between them, by turning the member, the gripping lugs may be brought into cooperative relation with the flanges of the I brake beam 13. At its outer end, 50 each of these hooks or gripping lugs has a

flat terminal portion 14, the two parts being adapted to lie against the web of beam 13 and on opposite sides thereof. These ears 14 are apertured as illustrated, and are adapted to be fastened to the web of the 60 brake beam by means of rivets, as is obvious.

In order to strengthen these flange-engaging lugs, each is provided with integral marginal ribs or beads 15, clearly shown on Figs. 1, 3 and 4. Projecting in the opposite 65 direction from the base 10 is a yoke or stirrup 16 held in place by a pair of integral brackets 17. At its outer end, this yoke is enlarged at 18, and is centrally and circularly apertured at 19 to form a bearing. The base 10 of this member, which in normal position lies against the oppositely-extended flanges 13^a of the brake beam, has a comparatively large round aperture 20, the diameter of which is at least equal to the greatest cross-sectional dimension of the barrel described below.

The barrel or reversible part of the fulcrum has at one end a round journal or plate 21 of substantially the same diameter as the 80 aperture 20, and adapted to fit and turn therein. At its opposite end, this barrel has a similar round plate 22, from the outer face of which projects a smaller integral journal or stub shaft 23 intended to fit and rotate 85 in the hole 19 of the yoke or stirrup 16. Connecting the two plates 21 and 22, and integral therewith, is a pair of flat plate members 24—24 adapted to receive between them the 90 brake-operating lever 25, a portion of which is indicated in Fig. 3. Round holes 26 are provided in the members 24, and in alignment, through which may be passed the hinge bolt or rivet 27 which fastens the lever 25 in the fulcrum. In order to apply this 95 reversible fulcrum to the brake beam, the barrel is inserted within its companion supporting member through the aperture 20, and when fully inserted the journals 21 and 23 neatly fit within their bearings 20 and 100 19, so that the barrel may be oscillated or turned to accommodate operating levers 105 disposed at various angles. After the barrel has been introduced into the main member of the fulcrum, the latter is applied to the brake beam in such a manner that the brake beam passes between the flange-engaging lugs or hooks 11 and 12, and then, by turning the fulcrum, the lugs 11 and 12 110 are brought into flange-gripping position,

and the ears 14 lie flat against opposite sides of the beam web, to which they may be riveted. The fulcrum is now in position for operation, and as soon as the lever 25 has been bolted or riveted between the pair of plates 24, the parts are ready for actuation. It should be noted that the brake beam itself keeps the barrel in position and prevents its accidental displacement or removal from its supporting yoke or stirrup. As soon, however, as the main body of the fulcrum has been detached from the brake beam, the barrel can be readily removed by passing it through the aperture 20.

15. To those skilled in the art it will be apparent that slight changes may be made in the parts of the fulcrum without departing from the spirit of my invention.

As illustrated, my improved device consists only of two members; but it will be apparent that these two members may be built up or constructed of a number of parts fastened together, if desired.

I claim:

25. 1. A brake-beam fulcrum, comprising a member adapted to be fastened to the brake beam and having a circular aperture blocked or obstructed by the brake beam when the member is secured thereto, said member also having a circular bearing at its end remote from the beam, and a barrel to which the operating lever is adapted to be pivoted, revoluble in said member and having journals fitting in said circular aperture and bearing, 35 said aperture comprising means whereby said barrel may be inserted in and removed from said member when the latter is detached from the brake beam, substantially as described.

40. 2. A brake-beam fulcrum comprising a member having oppositely-disposed grip-

ping-lugs to engage the flanges of the brake beam and spaced apart sufficiently to permit the entrance of the beam between them, whereby by turning the member its lugs 45 are brought into gripping relation with the flanges of the beam, said member having a portion adapted to lie against said flanges and having a circular aperture or bearing, said member also having a yoke or stirrup 50 with a bearing, and a barrel to which the operating lever is adapted to be secured, adapted to fit in said yoke or stirrup and having journals coöoperating with said bearings whereby the position of the barrel may 55 be adjusted, substantially as described.

3. A brake-beam fulcrum comprising a member having oppositely-disposed gripping lugs to engage the flanges of the brake beam and spaced apart sufficiently to permit the entrance of the beam between them, whereby by turning the member its lugs are brought into gripping relation with the flanges of the beam, said member having a portion to lie against said flanges and having 60 a circular aperture or bearing, said member also having a yoke or stirrup with a bearing, and a barrel to which the operating lever may be secured, adapted to fit in said yoke or stirrup and having journals coöoperating with 65 said bearings whereby the position of the barrel may be adjusted, said circular aperture or bearing comprising means whereby said barrel may be inserted in and removed from said member when the latter is detached from the brake beam, substantially 70 as described.

JAMES W. HOUSER.
